CLAIM

The ornamental design for a combined distributor and tamper, as shown and described.

DESCRIPTION

FIG. 1 is a right, front, and top perspective view of a combined distributor and tamper, showing my design.

FIG. 2 is a left, rear, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a cross-sectional view of the combined distributor and tamper of FIG. 1, taken along section line 9-9 as depicted in FIG. 5.

The broken lines in the drawings depict portions of the combined distributor and tamper that form no part of the claimed design.
